UNITED STATES PATENT OFFICE.

BRUCE NUNNALLY, OF JACKSONVILLE, TEXAS.

PLOW.

No. 845,254.

Specification of Letters Patent.

Patented Feb. 26, 1907.

Application filed May 8, 1906. Serial No. 315,797.

To all whom it may concern:

Be it known that I, BRUCE NUNNALLY, a citizen of the United States, residing at Jacksonville, in the county of Cherokee and State 5 of Texas, have invented a new and useful Plow, of which the following is a specification.

This invention relates to agricultural implements, and more particularly to beams 10 for holding one or more plow-standards or harrow-teeth.

Another object is to provide a beam, to 15 which notched devices, such as plow-standards or harrow-teeth, may be connected, so as to be capable of lateral or vertical adjustment.

With the above and other objects in view the invention consists of a beam having parallel cross-strips extending above and below it, and these strips are adapted to project 20 into notched devices, such as teeth or plow-standards, and means are provided whereby these devices can be securely clamped upon the cross-strips and in any positions to which they may be adjusted.

25 The invention also consists of certain other novel features of construction and combinations of parts, which will be hereinafter more fully described, and pointed out in the claims.

In the accompanying drawings is shown 30 the preferred form of the invention.

In said drawings, Figure 1 is a side elevation. Fig. 2 is a plan view showing by dotted lines the manner of adjusting the cross-strips. Fig. 3 is a detail view of a plow- 35 standard. Fig. 4 is a similar view of a back plate, and Fig. 5 is a detail view of a harrow-tooth.

Referring to the figures by characters of reference, 1 is a beam of any suitable proportions having handles 2 connected to its rear 40 end. Secured to the upper and lower faces of the beam adjacent the handles are parallel cross-strips 3, said strips being fastened, preferably at their centers, to the beam by means 45 of a bolt 4. Connecting-pins 5 are fastened to the ends of the cross-strips, and secured to these pins are brace-rods 6, which are fastened to the sides of the beam and serve to hold the cross-strips against movement. If 50 the beam is to be used for plowing purposes, a plow-standard may be fastened to the cross-strips 3 at each side of the beam. The standards 7 used in connection with the strips have longitudinally-extending slots 8 therein, and notches 9 are formed in the rear faces 55 thereof and are adapted to receive the front

edges of cross-strips 3. A back plate 10 bears upon the opposite edges of the cross-strips and has an enlargement 11, which fits snugly between the strips and prevents 60 the back strip from rotating. A bolt 12 extends through each of these back strips and through the slot in one of the plow-standards and is fastened therein by means of a nut 13 or in any other preferred manner. Obviously by tightening this nut the plow-standard 65 will be clamped upon the front edges of the cross-strips, and by loosening the nut said standard can be adjusted vertically or can be moved from or toward the plow-beam, 70 after which it can be resecured.

Instead of using plow-standards harrow-teeth 14 may be employed, each tooth having notches 15 to receive the front edges of the cross-strips and also having a back plate 75 10, to which it is connected by a bolt 12. Any desired number of these harrow-teeth may be arranged at each side of the beam, and said teeth can be readily secured in desired positions in the manner described. If 80 it is desired to use the beam in connection with a single plow-standard, the two cross-strips 13 can be removed by withdrawing the bolt 4 and detaching the brace-rod 6, and a standard can then be connected to a beam in 85 the ordinary manner.

The implement herein described will be found to be of considerable utility in that it can be used either as a single or double plow or as a harrow. It can be manufactured at 90 slight cost, and in view of the manner in which the notched faces are connected to it the same can be adjusted to suit various conditions.

The preferred form of the invention has 95 been set forth in the foregoing description; but I do not limit myself thereto, as I am aware that modifications may be made therein without departing from the spirit or sacrificing any of the advantages thereof, and I 100 therefore reserve the right to make such changes as fairly fall within the scope of the invention.

What is claimed is—

1. In an agricultural implement of the 105 character described the combination with a beam; of parallel cross-strips secured to opposite faces thereof and each having a straight uninterrupted edge, an element having notches therein adapted to receive the 110 straight edges of the cross-strips, a back plate slidably mounted on the opposite edges of

said strips, and means connecting said plate and the notched element for clamping the plate and element upon opposite edges of the strips, said plate and element being slidable longitudinally of the strips.

- 5 2. In an agricultural implement of the character described the combination with a beam; of parallel cross-strips connected to opposite faces of the beam, each strip having
10 a straight uninterrupted edge, an element having a curved face provided with notches adapted to receive the straight edges of the strips, a back plate slidably engaging the

strips, and means connecting said plate and notched element for clamping them upon opposite edges of the strips, said plate and element being slidable longitudinally of the strips, and said element being adjustable longitudinally upon the strips.

15 In testimony that I claim the foregoing as my own I have hereto affixed my signature in the presence of two witnesses.

20 BRUCE NUNNALLY.
